(57) **CLAIM**

The ornamental design for a battery pack, as shown and described.

DESCRIPTION

FIG. 1 is a top, front, and right side perspective view of an embodiment of a battery pack according to my new design; FIG. 2 is a left side elevation view thereof; FIG. 3 is a right side elevation view thereof; FIG. 4 is a top plan view thereof; FIG. 5 is a bottom plan view thereof; FIG. 6 is a front elevation view thereof; and, FIG. 7 is a rear elevation view thereof.

The dot-dash broken lines represent boundaries of the claimed design and form no part of the claimed design. The dash-dash broken lines depict portions of the battery pack that form no part of the claimed design.

1 Claim, 3 Drawing Sheets
